CODED TRACK CIRCUIT RAILWAY
SIGNALING SYSTEM

Arthur L. Jerome, Edgewood, Pa., assignor to The
Union Switch & Signal Company, Swissvale,
Pa., a corporation of Pennsylvania

Application July 22, 1947, Serial No. 762,617

5 Claims. (Cl. 246—3)

1

My invention relates to coded track circuit railway signaling systems for governing the movement of traffic over stretches of single track over which traffic moves in two directions. More particularly, my invention relates to an improved absolute permissive block signaling system employing cascade-connected reversible coded track circuits, for use in a centralized traffic control system in which the traffic direction is set up and the head block signals are cleared by manual control from a central office by means of an intermittently operated communication system, while the intermediate signals, which are controlled solely by the track circuits, are cleared automatically in one direction or the other in accordance with the direction of energization of the track circuit system.

In an absolute permissive block signaling system, such as is herein disclosed, directional stick relays are provided in connection with the intermediate signals, each of which is normally arranged to become energized when a train passes the associated signal at clear or caution, and when energized prepares a circuit for energizing the next signal in the rear, governing traffic movements in the same direction to permit that signal to indicate caution as soon as the block section in advance is vacated by a train.

The principal object of my invention is the provision of improved means for controlling these directional stick relays by the track relays of a coded track circuit system, so that each directional stick relay becomes energized when the code operation of the associated track relay ceases due to a train entering the corresponding track section in the established direction, but not when the operation of the track relay is discontinued due to an opposing train overrunning a head block signal nor when the track circuit system is manually deenergized in preparation for reversing the direction of traffic.

A further object of my invention is to provide improved means of the type described which is arranged so that the equipment at each intermediate signal location in the stretch is substantially self-contained and does not depend for its operation on special energy impulses transmitted over the track rails from an adjacent signal location.

Another object of my invention is to provide improved means of the type described which is arranged so that the operation of the equipment is independent of changes in operating conditions, such as changes in ballast resistance or in the voltage of the batteries from which energy is supplied to the track circuits.

A further object of the invention is to arrange the equipment so that the approach relay which governs the lighting of the signal for one direc-

tion of traffic also serves to govern the directional stick relay for the opposite direction of traffic.

In practicing my invention I employ at each intermediate signal location means operative on release of the code detecting means which governs the signal to momentarily connect in series across the rails of the track section in advance of the signal a source of current and an auxiliary relay. This relay has a normally released contact which becomes picked up only if the energy supplied from the source through the relay winding is of the value which is supplied when the rails of the section are shunted by a train located at or near the entrance end of the section so that the relay will pick up if release of the code detecting means was caused by entrance of a train into the section at that end of the section but will remain released if release of the code detecting means was caused by any other condition. The picking up of this relay governs energization of the directional stick relay.

The provision of an auxiliary relay and battery, connected to operate as described above, does not comprise my invention per se, but is described and claimed in an application for Letters Patent of the United States, Serial No. 148,967, filed on March 10, 1950, by Crawford E. Staples, for Directional relay control circuits for railway signaling systems, which application is assigned to the same assignee as the present application.

At double intermediate signal locations the code following approach relay which governs lighting of the lamp of the signal for one direction of traffic is employed to govern the directional stick relay associated with the signal for the other direction. Where an approach relay is employed for this purpose its adjustment is controlled so that during the period in which the relay is connected across the track rails as a result of release of a code detecting means, the relay contact will pick up only if there is supplied through the relay winding energy of the value which is supplied only if the rails of the associated track section are shunted by a train located relatively near the approach relay.

Other objects of my invention and features of novelty will be apparent from the following description taken in connection with the accompanying drawings.

I shall describe one form of apparatus embodying my invention and shall then point out the novel features thereof in claims.

Referring to the accompanying drawings, Figs. 1A, 1B and 1C, placed side by side in the order listed with Fig. 1A at the left, illustrate the track plan and wayside circuits for a typical single track block embodying the apparatus of my invention. The block shown includes two sections,

over which opposing traffic movements are governed by the entering head block signals 2RA and 2RB, Fig. 1A, and by the similar signals 4LA and 4LB of Fig. 1C.

Similar reference characters refer to similar parts in each of the several views.

Energy for the operation of the relays other than the track relays is furnished by suitable sources of direct current, not shown, whose positive and negative terminals are designated B and C, respectively. Each track switch and each railway signal is identified by a number identifying its location, the signal designations also including the suffix L or R to indicate the corresponding direction of traffic movements to the left or right, respectively. Each relay is identified by a characteristic letter or combination of letters, prefixed by the designation of the switch or signal with which it is associated. The track relays 2RTR, 6LTR, 6RTR, and 4LTR, and also the approach relays 6RAR and 6LAR are code following relays of the biased polar type, such as shown for example in Letters Patent of the United States No. 2,057,605, issued October 13, 1936, to Herman G. Blosser. These relays are constructed and arranged so that the contacts of the relay are normally biased to their released position and will pick up when and only when energy flows through the winding in the direction indicated by the arrow thereon.

The periodically operating contacts of the code following relays are distinguished from those of the other quick acting relays by horizontal dotted lines indicating their closed positions and the contacts of slow acting relays are identified in the conventional manner by the vertical arrows thereon. It is to be understood that the slow acting relays having condensers bridged across their windings have release periods of about five seconds.

Each of the wayside signals shown in the drawings is of the well-known color-light type, having a green lamp G, a yellow lamp Y, and a red lamp R, with the exception of signals 2LB and 4RB, which do not include the green lamp G. The signals at the ends of the single track section are shown as being continuously lighted, while the intermediate signals 6L and 6R are arranged to be lighted only when the track section in the rear of each signal is occupied by a train.

Inasmuch as my invention relates to wayside apparatus, the centralized traffic control system by means of which the direction of energization of the signal circuits and the clearing of the entering signals is made subject to manual control from a central office is not shown herein, but it is to be understood that this is preferably a remote control system of the code type such as that disclosed in Letters Patent of the United States No. 2,229,249, issued January 21, 1941, to Lloyd V. Lewis, for Remote control systems, or more particularly, as a modification thereof described in a publication entitled "Centralized Traffic Control System-Time Code Scheme, Manual No. 506A," published by the Union Switch and Signal Company, Swissvale, Pennsylvania. For an understanding of my invention, it will suffice to point out that the remote control system has a field station at the end of each block which is connected with a control office by a line circuit over which codes are transmitted in either direction for selective communication between the office and the different stations, one at a time. The control codes transmitted to the stations serve to operate a group of control relays of the

stick polar type, in accordance with the positions of control levers at the office. Two such control relays are shown herein at each station, and these comprise a traffic relay such as relay 2RFS, Fig. 1A, which governs the direction of traffic movements in the single track block by cooperation with a similar relay 4LFS at the opposite end of the single track block, shown in Fig. 1C, and also include two code signal control relays, such as the relays 2RHS or 4LHS, by which the clearing of the correspondingly designated entering signals is made subject to manual control from the office.

Each traffic relay 4LFS or 2RFS when in its normal position as shown, with its left-hand contacts closed, designates its location as the entrance end of its block, in which position the traffic relay enables the adjacent entering head block signal to be cleared under proper conditions, in response to the reversal of the associated code signal control relay 2RHS or 4LHS. Each traffic relay when reversed, with its right-hand contacts closed, designates its location as the exit end of the block. In this position the traffic relay supplies energy to the signal circuits for the block to enable the signals which govern traffic movements toward its location to be cleared.

The trackway system includes continuous track circuits for all main track. The detector sections 1T and 3T at the ends of the block each have a conventional track circuit including a track relay, such as 1TR, which is normally energized by a battery 1TB. The remaining track circuits 2R-6LT and 6R-4LT of the single track block are of the reversible coded type, connected in cascade when the block includes two or more sections, and provide means for controlling the signals for both directions to provide three indications and also for indicating at either end whether or not the block is occupied, without line wires.

In this application only the portions of the wayside apparatus essential to the understanding of this invention have been shown and the remainder of the equipment may be arranged in any of several arrangements well known in the railway signaling art.

The present invention relates more particularly to the coded track circuit apparatus, and is an improvement upon that disclosed in an application for Letters Patent of the United States, Serial No. 596,470, filed May 29, 1945, by Henry S. Young for Railway traffic controlling apparatus. In the system of this Young application, the coded track circuits are normally deenergized and are set up by manual control by reversing the traffic relay at the exit end of the block for the desired direction of traffic movement, and then reversing the code signal control relay for the entering signal at the other end of the block. The system of the Young application is also arranged so that when a train vacates the block and an indication of that fact has been transmitted to the office, the operated traffic relay is restored automatically to normal, and the wayside circuits thereby restored to their normal deenergized condition. This mode of operation may be employed in connection with the track circuits of my invention, or they may be left energized until a reversal of the traffic direction is required to thereby provide a normally energized system. It is also to be understood that the remote control system preferably includes means for preventing the operation of the traffic and signal control relays

except under the proper traffic conditions, so that a signal cannot be put to stop by the operation of any lever other than its control lever, one arrangement suitable for this purpose being disclosed in the above-mentioned Young application.

In the coded track circuit system as disclosed herein, the coded currents are generated by code transmitters of the pendulum type designated 180CT and 75CT, which are energized continuously and operate their contacts periodically at a rate of 180 or 75 times per minutes, respectively, to periodically operate a transmitter relay such as relay 2RCT, by which the coded energy of the selected frequency is supplied to the track rails.

Each code following track relay, such as relay 2RTR, is provided with a slow release, front contact repeater, such as the relay 2RTF, which remains picked up as long as the track relay is responding to coded energy.

The code responsive apparatus at the different signal locations is substantially similar and its operation will be understood from a description of that of Fig. 1A, where it will be seen that the closing of front contact *a* of relay 2RTR in response to the supply of an impulse of coded energy to the winding of relay 2RTR establishes the circuit for supplying energy to the winding of relay 2RTF. When the contacts of relay 2RTF pick up, its front contact *a* establishes a circuit for supplying energy to a code following repeater relay 2RTP each time that the relay 2RTR releases its contact *a*. Additionally, when relay 2RTF picks up, its contact *b* establishes a circuit for supplying energy to the primary winding of decoding transformer 2DT over contact *a* of relay 2RTP. As the contacts of relay 2RTP are recurrently picked up and released in response to the code following operation of contact *a* of relay 2RTR, contact *a* of relay 2RTP alternately energizes the lower half and the upper half of the primary winding of decoding transformer 2DT. As a result, current is induced in the secondary winding of transformer 2DT which is rectified by contact *b* of relay 2RTP and supplied to the winding of a slow acting code detector relay 2RH. It will be seen that the relay 2RH will be energized when and only when the track relay 2RTR is following code. Transformer 2DT also supplies code frequency energy to the decoding unit 186DU which is of a type well known in the art. The decoding unit 186DU is constructed and arranged so that it will supply energy of a value sufficient to pick up the contacts of relay 2RD when and only when the frequency of the energy supplied to the decoding unit from transformer 2DT is of the order of 180 cycles per minute. Accordingly, relay 2RD will be energized when and only when the code following relay 2RTR is responding to 180 code.

The circuits for controlling track switches 1W and 3W which lead to the passing tracks at the ends of the single track block have been omitted in order to simplify the drawings, and it will be understood that when switch 1W is locked in its normal position as shown, a normal switch repeating relay 1NWP is energized, and when switch 1W is locked in its reverse position, a reverse switch repeating relay 1RWP is energized over the contacts N and R of a circuit controller actuated by switch 1W. These relays serve to select the signal lighting circuits for signals 2RA or 2RB, in accordance with the position of the switch 1W, the selected signal displaying a yellow aspect when the code detector relay 2RH is energized, or displaying a green aspect if relay 2RD is also energized.

The operation of the system is generally similar for both directions of traffic movement and the circuits of Fig. 1C, therefore, are similar to those of Fig. 1A, except that they are oppositely directed. Likewise, the apparatus at the intermediate signal location of Fig. 1B is similar for each direction but oppositely directed. In Fig. 1B, but one set of decoding apparatus is used, this being arranged for either direction of operation depending upon which of the track relays is operated, and in addition, a pair of directional stick relays, such as 6RSR and 6LSR are provided for controlling the energization of the track circuit system as required for following train movements in either direction.

In describing in detail the operation of the system embodying my invention, it is assumed that the apparatus is in its normally deenergized condition, as shown. It will now be assumed that the operator desires to move a train from right to left through the block. By operation of the control levers at the control office, the traffic relay 2RFS of Fig. 1A, and the code signal control relay 4LHS of Fig. 1C are operated to their reverse positions.

At this time, since signal 2LA is at stop, the circuit for supplying energy to the signal repeater relay 2LAPC is interrupted and the contacts of relay 2LAPC are released. The circuit for controlling relay 2LAPC is not shown, but it may be of any of several well-known types in which the relay is energized when and only when signal 2LA displays a yellow or a green aspect. Accordingly, a circuit is established to supply energy of 75 code frequency to the transmitting relay 2RCT. This circuit is traced from terminal B, over contact *a* of code transmitter 75CT, over back contact *a* of relay 2LAPC, front contact *a* of relay 1TR, over reverse polar contact *a* of relay 2RFS and through the winding of relay 2RCT to terminal C, whereby the contacts of the relay 2RCT are operated at the 75 code rate.

When contact *a* of relay 2RCT picks up, it interrupts the connection of track relay 2RTR to the rails of section 2R-6LT, and establishes a circuit for supplying energy from the battery 2RTB through the winding of relay 2RTR and the rails of section 2R-6LT to the winding of relay 6LTR, shown in Fig. 1B. This circuit is traced from the positive terminal of battery 2RTB, over front contact *a* of relay 2RCT, through the winding of relay 2RTR, over rail 5 of section 2R-6LT, through the winding of relay 6LTR, Fig. 1B, over back contact *a* of relay 6LCT, and over rail 6 to the negative terminal of battery 2RTB. The direction of flow of energy is such that the contact of relay 2RTR remains released, and the contact of relay 6LTR becomes picked up.

When contact *a* of relay 2RCT releases, the circuit traced above is interrupted, and the contact of relay 6LTR releases. Accordingly, at this time, the coded energy supplied to the left-hand end of the rails of section 2R-6LT causes the contacts of relay 6LTR to be operated at the 75 code rate. The recurrent operation of the contact of relay 6LTR causes energy to be supplied over front contact *a* of the relay to the winding of relay 6LTF, and as a result, the contacts of relay 6LTF pick up and remain picked up as long as relay 6LTR is following code.

When contact *a* of relay 6LTF picks up, it establishes a circuit for supplying energy to the code following repeater relay 6TP each time relay 6LTF releases its contact *a*. This circuit is traced from terminal B, over back contact *a* of

relay 6LTR, front contact *a* of relay 6LTF, back contact *a* of relay 6RTF, and through the winding of relay 6TP to terminal C. As a result, the relay 6TP will recurrently pick up and release its contacts in accordance with the operation of contact *a* of relay 6LTR.

The primary winding of decoding transformer 6DT is now supplied with energy by a circuit including front contact *c* of relay 6LTF and contact *a* of relay 6TP. The recurrent operation of contact *a* of relay 6TP causes energy to be alternately supplied to the upper and lower portions of the primary winding of transformer 6DT, and as a result, an alternating current is induced in the secondary winding of the transformer. This energy is rectified mechanically by contact *b* of relay 6TP, and is supplied to the winding of the code detecting relay 6H to thereby cause the contacts of relay 6H to pick up and remain picked up as long as relay 6TP is following code. Additionally, energy is supplied from the decoding transformer 6DT to the resonant decoding and rectifying unit 180 DU, but since the code rate at this time is only 75 times per minute, the energy supplied from the decoding unit 180DU to the relay DR is insufficient to pick up the contacts of relay DR.

When relay 6H picks up, its contact *a* establishes the circuit for supplying energy to the code transmitter 180CT, and contact *b* of relay 6H establishes a circuit for supplying energy to the transmitting relay 6RCT, which circuit is traced from terminal B, over contact *a* of code transmitter 180CT, front contact *b* of relay 6H, over front contact *d* of relay 6LTF, over back contact *b* of relay 6RSR, and through the winding of relay 6RCT to terminal C. As a result, the contacts of relay 6RCT are picked up and released at the 180 code rate. Additionally, contact *c* of relay 6H establishes the circuit for connecting the condenser Q to the source and a charge of energy is built up in the condenser.

When the contacts of relay 6RCT pick up, a circuit is established to supply energy from battery 6RTB to relay 4LTR, Fig. 1C. This circuit is traced from the positive terminal of battery 6RTB, over front contact *a* of relay 6RCT, over front contact *b* of relay 6RCT in multiple with the winding of relay 6RTR, over rail 6 of section 6R-4LT, through the winding of relay 4LTR, over back contact *a* of relay 4LCT, through rail 5 of section 6R-4LT, and through the resistor R1 in multiple with the winding of relay 6LAR and resistor R2 to the negative terminal of battery 6RTB. A portion of the adjustable resistor R2 is shunted at this time by the circuit governed by back contact *b* of relay 6RTF, by the relay 6LAR and the resistors R1 and R2 associated therewith are selected and adjusted so that the value of energy which flows through the approach relay 6LAR at this time is insufficient to pick up the relay contact. The direction of flow of energy is such that relay 4LTR will pick up its contact and relay 6RTR will remain released. The shunting of the winding of relay 6RTR by front contact *b* of relay 6RCT affords a lower resistance to the flow of energy in the circuit traced above. When the contacts of relay 6RCT release, the circuit traced above is interrupted, and the contacts of relay 4LTR release. Accordingly, at this time, the contact of relay 4LTR in Fig. 1C picked up and released 180 times per minute in response to the coded energy supplied over the rails of section 6R-4LT.

Each time relay 4LTR picks up, energy is supplied over front contact *a* to the winding of relay

4LTF, so that at this time, the contacts of relay 4LTF are picked up. Each time contact *a* of relay 4LTF releases, energy is supplied over front contact *a* of relay 4LTP to the winding of relay 4LTP. Accordingly, the contacts of relay 4LTP are picked up and released 180 times per minute in accordance with the operation of contact *a* of relay 4LTF.

The primary winding of decoding transformer 10 4DT is now supplied with energy by a circuit including front contact *b* of relay 4LTF and contact *a* of relay 4LTP. The recurrent operation of contact *a* of relay 4LTP causes energy to be alternately supplied to the upper and lower portions of the primary winding of decoding transformer 4DT, and as a result, an alternating current is induced in the secondary winding of the transformer having a frequency corresponding to the code rate, which at this time is 180 per minute. 15 This energy is rectified mechanically by contact *b* of relay 4LTP and supplied to the winding of code detector relay 4LH to thereby cause the contacts of relay 4LH to pick up and remain picked up as long as relay 4LTP is following code. Additionally, energy is supplied from the decoding transformer 4DT to the resonant decoding and rectifying unit 180DU, and since this energy has a frequency of 180 cycles per minute, the decoding unit 180DU supplies sufficient 20 energy to the relay 4LD to pick up its contacts. 25

Since it is assumed that the code signal control relay 4LHS has been reversed by the central office operator and since switch 3W is normal, the picking up of relays 4LH and 4LD establishes 30 a circuit for supplying energy to the green lamp of signal 4LA. This circuit is traced from terminal B, over reverse polar contact *a* of relay 4LHS, over front contact *b* of relay 3TR, over front contact *a* of relay 3NWP, over front contact *a* of relay 4LH, front contact *a* of relay 4LD, and through the green lamp G of signal 4LA to terminal C. Accordingly, at this time signal 4LA will display a green aspect, indicating "proceed."

If the operator now clears signal 2LA by means 45 of circuits not shown, the relay 2LAPC will become picked up, and its contact *a* transfers the circuit for supplying energy to relay 2RCT from contact *a* of code transmitter 15CT to contact *a* of code transmitter 180CT. As a result, relay 50 2RCT operates its contacts 180 times per minute and the supply of energy from battery 2RTB to the rails of section 2R-6LT is coded at that rate.

Relay 6LTR, Fig. 1B, now operates its contacts 180 times per minute in response to the 180 code 55 supplied to its winding, and repeater relay 6TP also operates its contacts 180 times per minute.

Accordingly, energy of a frequency of 180 cycles per minute is supplied from decoding transformer 6DT to the decoding unit 180DU, which now 60 supplies sufficient energy to relay 6D to cause the relay to pick up its contacts, thereby conditioning the signal 6L to display a proceed or green aspect when energy is supplied to its lamps.

The movement of a train from right to left 65 through the single track block will now be traced, assuming that the signals 2LA, 6L, and 4LA have been conditioned to indicate proceed as above described.

When the train moves past signal 4LA and 70 enters the detector section 3T, detector track relay 3TR is shunted and its contacts release. Contact *b* of relay 3TR interrupts the circuit previously traced for supplying energy to the green lamp G of signal 4LA and establishes the supply 75 of energy to the red lamp R of the signal.

It is to be understood that at this time the code signal control relay 4LHS is restored automatically to normal and an indication of the occupancy of section 3T is transmitted to the control office as described in the Manual identified above.

When the train enters section 6R—4LT, the relay 4LTP is shunted and its code following operation ceases. Contact *a* of relay 4LTP releases and remains released at this time, and the supply of energy to relay 4LTF is cut off as a result, but it retains its contacts picked up until the energy stored in the condenser connected across its winding is dissipated. The contacts of relay 4LTP are picked up continuously for this time interval, but energy is no longer supplied to relays 4LH and 4LD from the transformer 4DT, and the contacts of these relays release.

Subsequently, the contacts of relay 4LTF release, interrupting the supply of energy to relay 4LTP and to the primary winding of transformer 4DT.

At this time, relay 6RCT, Fig. 1B continues to operate its contacts, supplying coded energy from battery 6RTB through resistor R1 and also through the winding of relay 6LAR and a portion of resistor R2 to the rails of section 6R—4LT. Due to the shunting effect of the wheels and axles of the train, the current supplied to the rails from battery 6RTB increases as the train approaches signal 6L. The various parts of the equipment are arranged and proportioned so that when the train advances within a substantial distance of the signal 6L, as for example, 4000 feet, the value of current which flows through the winding of approach relay 6LAR becomes sufficient to cause the relay to operate its contact. Each time contact *a* of relay 6LAR picks up, energy is supplied to the slow release approach repeater relay 6LAP by the circuit which is traced from terminal B, over front contact *a* of relay 6LAR, back contact *b* of relay 6RTF, and through the winding of relay 6LAP to terminal C. Accordingly, relay 6LAP is energized at this time and its front contact *a* establishes the circuit for supplying energy to the green lamp G of signal 6L, which circuit is traced from terminal B, over front contact *a* of relay 6LAP, front contact *d* of relay 6H, over front contact *a* of relay 6D, and through the green lamp G of the signal to terminal C, thus causing signal 6L to display a proceed aspect to the approaching train.

When the train passes signal 6L and enters section 2R—6LT, relay 6LTF is shunted and its contact *a* releases and remains released and cuts off the supply of energy to relay 6LTF. However the relay 6LTF is slow in releasing and after release of relay 6LTF, the circuit including back contact *a* of relay 6LTF for supplying energy to relay 6TP is established and the contacts of relay 6TP remain picked up for a substantial time interval. The cessation of operation of the contacts of relay 6TP cuts off the supply of energy from transformer 6DT to relays 6H and 6D and these relays release after a short time interval which is less than the time required for relay 6LTF to release. When contact *d* of relay 6H releases the supply of energy to the green lamp G of signal 6L is interrupted, and the circuit is established for supplying energy to the red lamp R of signal 6L.

The relays 6LTF and 6RTF are selected and arranged with condenser snubs of sufficient capacity so that these relays will remain picked up for a comparatively long time interval after the

supply of energy thereto has been interrupted by the release of the track relays.

Accordingly, there will be a substantial time interval between the release of relay 6H and the release of relay 6LTF after the supply of energy to each of these relays has been cut off by the cessation of operation of the contact of relay 6LTF. During this time interval, a circuit is established for supplying energy from the condenser Q to the transmitter relay 6LCT. This circuit is traced from the left-hand element of condenser Q, over back contact *c* of relay 6H, front contact *f* of relay 6LTF, over back contact *a* of relay 6LSR, and through the winding of relay 6LCT to terminal C and thus to the right-hand element of condenser Q.

When the contacts of relay 6LCT pick up, energy is supplied from battery 6LTB through the winding of relay 6RAR over the circuit which is traced from the positive terminal of battery 6LTB, over front contact *a* of relay 6LCT, front contact *b* of relay 6LCT and the winding of relay 6LTF connected in multiple, through rail 5, through the wheels and axles of the train, through rail 6, and thence to the negative terminal of battery 6LTB through the resistor R4 and winding of relay 6RAR in series which are connected in multiple with resistor R3.

At this time, contact *g* of relay 6LTF is picked up, causing the entire amount of resistance of resistor R4 to be inserted in the circuit of relay 6RAR. However, with the train having just entered the section the resistance in the above circuit is comparatively low, and the relay 6RAR and other portions of the circuit are selected so that, notwithstanding the fact that the whole of resistor R4 is in series with the winding of relay 6RAR, the current flow through the relay winding at this time is sufficient to cause the relay to pick up its contact.

When relay 6RAR picks up, its front contact *a* establishes a circuit for supplying energy to the directional stick relay 6LSR. This circuit is traced from terminal B, over front contact *a* of relay 6RAR, front contact *b* of relay 6LTF, and through the winding of relay 6LSR to terminal C. When the contacts of relay 6LSR pick up, a stick circuit is established to maintain the relay 6LSR energized and is traced from terminal B, over back contact *a* of relay 6H, over front contact *b* of relay 6LSR, and through the winding of relay 6LSR to terminal C.

Additionally, when relay 6LSR picks up, its contact *c* interrupts the circuit previously traced for supplying energy to the winding of relay 6LCT, and its contacts release and interrupt the supply of energy from battery 6LTB to relay 6RAR so that relay 6RAR releases and interrupts the pick-up circuit of relay 6LSR. The relay 6LCT is made slightly slow in releasing by means of a snubbing resistor connected across the winding of relay 6LCT and after the supply of energy to the winding of relay 6LCT is interrupted, its contacts remain picked up for a short time interval; thus assuring that relay 6RAR will remain picked up and maintain the supply of energy to relay 6LSR for a sufficiently long time interval to insure that contact *b* of relay 6LSR establishes the stick circuit traced above.

A short time later, relay 6LTF releases and its contact *b* additionally interrupts the pick-up circuit which was previously traced for relay 6LSR. Also contact *g* of relay 6LTF again shunts part of the resistor R4 in series with the winding of relay 6RAR, but at this time relay 6LCT is re-

11

leased and the circuit of relay 6LCT is interrupted by contact *a* of relay 6LSR with the result that relay 6LCT will remain released so that relay 6RAR will not pick up again.

When contact *f* of relay 6LTF releases, a circuit is established for discharging any energy remaining in the condenser Q at this time. This circuit is traced from the left-hand element of condenser Q, over back contact *c* of relay 6H, back contact *f* of relay 6LTF, and over back contact *f* of relay 6RTF to terminal C and thus to the right-hand element of condenser Q.

At this time the code transmitter 75CT is set into operation by the supply of energy thereto by a circuit including front contact *c* of relay 6LSR.

When contact *b* of relay 6H releases due to the entrance of the train into section 2R-6LT, the circuit previously traced for supplying energy coded at 180 times per minute to the transmitter relay 6RCT is interrupted. Shortly thereafter, relay 6LSR picks up and its front contact *d* establishes a circuit for supplying energy coded at 75 times per minute to the transmitting relay 6RCT. This circuit is traced from terminal B, over contact *a* of code transmitter 75CT, front contact *d* of relay 6LSR, over back contact *b* of relay 6RSR, and through the winding of relay 6RCT to terminal C.

As a result, energy is now supplied to the rails of section 6R-4LT at the 75 code rate, and since the rear portion of the train still occupies section 6R-4LT, the approach relay 6LAR will now operate its contacts at the 75 code rate, and relay 6LAP will remain energized. The release time of relay 6LAP is made sufficiently long to bridge the time necessary for the equipment to operate to change the code speed of relay 6RCT from 180 to 75 times per minute.

When the train under discussion vacates section 6R-4LT, the removal of the shunt decreases the amount of current supplied thereto from the battery 6RTB, and as a result, the flow of energy through the winding of relay 6LAR falls below the value necessary to pick up the contact of relay 6LAR and it remains released. Accordingly, energy is no longer supplied to relay 6LAP over the circuit including front contact *a* of relay 6LAR, and after a time interval, the contact of relay 6LAP releases.

When contact *a* of relay 6LAP releases, it interrupts the circuit previously traced for supplying energy to the lamps of signal 6L, and, as a result, the red lamp R of signal 6L is extinguished.

At this time, as previously explained, energy coded 75 times per minute is supplied to the rails of section 6R-4LT by the operation of the contacts of transmitting relay 6RCT, and when the section is vacated relay 4LTR responds to the 75 code supplied over the rails of section 6R-4LT, energizing relays 4LTF and 4LH in a manner similar to that previously described. However, since the contacts of relay 4LTP are operating at the 75 code rate, the relay 4LD does not receive sufficient energy from decoding transformer 4DT and the decoding unit 180DU to pick up its contacts at this time. Consequently, if relay 4LHS is again reversed by the operator, signal 4LA will be cleared in a manner similar to that previously described, except that, since relay 4LD is released, the signal will display a yellow aspect, indicating that the next signal is displaying, or is conditioned to display, a red aspect.

As the train passes signal 2LA, and enters the 75

12

detector track section 1T, the detector track relay 1TR is shunted and its contacts release.

When contact *a* of relay 1TR releases, the circuit previously traced for supplying energy to transmitting relay 2RCT is interrupted so that coded energy is not supplied to the rails of section 2R-6LT after the train vacates that section. Additionally, it is to be understood that when the train under consideration enters section 1T, signal 2LA will be put to stop, and as a result, the relay 2LAPC will be deenergized and its contact will release.

When the train vacates section 1T, relay 1TR picks up, and contact *a* of relay 1TR again establishes the circuit for supplying energy to relay 2RCT. However, since the relay 2LAPC is released at this time, the circuit is governed by contact *a* of code transmitter 75CT, so that relay 2RCT supplies energy coded at the 75 code rate from battery 2RTB to the rails of section 2R-6LT.

The relay 6LTF follows the coded energy supplied thereto over the rails of section 2R-6LT, and as a result, the relays 6LTF and 6H pick up, as previously described. When contact *a* of relay 6H picks up, it interrupts the stick circuit previously traced for relay 6LSR, and relay 6LSR releases. When relay 6LSR releases, its front contact *d* interrupts the circuit previously traced for supplying energy to the relay 6RCT over contact *a* of code transmitter 75CT, and additionally, contact *c* of relay 6LSR interrupts the supply of energy to the code transmitter 75CT.

The code transmitter 180CT is now energized by the circuit including front contact *a* of relay 6H, and front contact *b* of relay 6H and front contact *d* of relay 6LTF again establish the circuit for controlling relay 6RCT over contact *a* of code transmitter 180CT. Also, the condenser Q is supplied with energy over front contact *c* of relay 6H.

Front contact *d* of relay 6H, and back contact *a* of relay 6D prepare the circuit for supplying energy to the yellow lamp of signal 6L should an approaching train cause the relay 6LAP to pick up, as previously described.

With the contacts of relay 6RCT operating at the 180 code rate, energy is supplied from battery 6RTB to the rails of section 6R-4LT at the rate of 180 impulses per minute. The response of relay 4LTR to the coded energy supplied thereto causes the relays 4LTF, 4LH, and 4LD to pick up, as previously explained. Energization of relay 4LD may be employed in any suitable manner to indicate that the entire single track stretch is vacant, but this means is not part of this invention and has been omitted in order to simplify this disclosure.

With the single track block unoccupied, and the traffic relay 2RFS reversed to set up the direction of movement from right to left, as described above, it is assumed that the operator at the control office restores the traffic relay 2RFS to normal.

When reverse contact *a* of relay 2RFS opens, the supply of energy to relay 2RCT is cut off. As a result, energy is no longer supplied from battery 2RTB over the rails of section 2R-6LT to relay 6LTF, and relay 6LTF releases and remains released.

As previously explained, the release of contact *a* of relay 6LTF results in the release shortly thereafter of the contacts of relay 6H, but the contacts of relay 6LTF remain picked up for

a relatively long time interval after release of relay 6LTR.

When contact *c* of relay 6H releases, it establishes the previously traced circuit for supplying energy from condenser Q to the winding of relay 6LCT. Accordingly, the contacts of relay 6LCT pick up and connect the battery 6LTB across the rails of section 2R—6LT in series with the resistor R4 and the winding of relay 6RAR in parallel with resistor R3.

At this time, contact *g* of relay 6LTF is picked up, and the entire resistance of resistor R4 is connected in series with the winding of relay 6RAR, but since section 2R—6LT is assumed to be unoccupied, the value of energy which flows through the winding of relay 6RAR is insufficient to pick up the contacts of the relay. As a result, the circuit previously traced for picking up the directional stick relay 6LSR is not established by front contact *a* of relay 6RAR, and relay 6LSR does not pick up at this time.

After a short time interval, the energy from condenser Q is dissipated, and relay 6LCT releases, cutting off the supply of energy from battery 6LTB to the rails of section 2R—6LT.

When relay 6LTF releases, its front contact *f* interrupts the circuit for supplying energy to relay 6LCT from condenser Q, and if relay 6LCT is not released, it releases at that time.

When relay 6H released its contacts, its front contact *a* interrupted the supply of energy to code transmitter 180CT, and front contact *b* of relay 6H interrupted the circuit for supplying energy to relay 6RCT over contact *a* of code transmitter 180CT, and since relay 6LSR does not pick up at this time to supply energy over its front contact *d* and contact *a* of code transmitter 15CT to the winding of relay 6RCT, the contacts of relay 6RCT remain released.

As a result, coded energy is no longer supplied from battery 6RTB over the rails of section 6R—4LT to the winding of relay 4LTR, and relay 4LTR releases, which results in the releasing of relays 4LTF, 4LTP, 4LH and 4LD, as previously explained.

The system is now restored to its normal or deenergized condition as shown in the drawings.

The energy impulse supplied to the rails of section 2R—6LT during the picked up period of relay 6LCT will pick up track relay 2RTR at the other end of the section, and relay 2RTF will pick up as a result. When contact *b* of relay 2RTF picks up it establishes the circuit for supplying energy to the primary winding of transformer 2DT with the result that a pulse of energy of small value is induced in the transformer secondary winding and is supplied therefrom to relay 2RH. When relay 6LCT releases, and the supply of energy to relay 2RTR is cut off, the circuit previously traced for energizing relay 2RTP is established, and relay 2RTP picks up, thereby causing a pulse of energy of normal value to be supplied through transformer 2DT to relay 2RH. After a comparatively long time interval, relay 2RTF releases, thereby interrupting the supply of energy to the primary winding of transformer 2DT and causing the release of relay 2RTP. At this time a pulse of energy of small value is supplied through transformer 2DT to relay 2RH. These pulses, however, are of such value and are separated by such time intervals as to be ineffective to pick up relay 2RH. Accordingly, the operation of the apparatus when returning to the deenergized state is such that false operation of the controlled signals cannot result.

From the foregoing it will be seen that the directional stick relay, such as relays 6LSR or 6RSR, is energized when the code operation of the associated track relay ceases as a result of a train entering the corresponding track section at the entrance end thereof, but is not energized if the code operation of the track relay ceases when the section is not occupied.

This result is secured by providing at each 10 intermediate signal location means effective upon release of the code detecting relay governed by a track relay at that location to temporarily connect the associated track battery and approach relay in series across the rails of the track section in advance of the signal. At this time the approach relay is adjusted so that energy sufficient to pick up the relay contact is supplied from the track battery through the winding of the approach relay only if a train is present at that end of the track section, while the directional stick relay is governed by the approach relay so as to be picked up if the approach relay picks up at this time.

When the track battery is connected across the 25 track rails at an end of a track section in series with the winding of the approach relay the energy supplied through the winding of the approach relay is of a high value if a train occupies that end of the track section but is of a low value if the track section is not occupied, or if a train is present in a distant portion of the track section so that a considerable length of track rail is included in the circuit of the track battery and approach relay.

Occupancy of an end portion of a track section 30 produces a much greater increase in the value of the energy supplied from the track battery through the winding of the approach relay than is produced by variations in other conditions, such as changes in ballast resistance or in the 35 voltage of the track battery. Accordingly, at the time the code detecting relay releases the approach relay may be adjusted to respond only to energy of relatively high value so that if that end of the track section is not occupied, the approach relay will not respond to energy of the 40 value supplied as a result of high battery voltage or low ballast resistance, or as a result of both 45 conditions, but so that the approach relay will be certain to respond if that end of the track section is occupied.

As a result this method of controlling the 50 directional stick relay insures that the relay will be picked up to cause coded energy to be supplied to the track stretch behind a train when release 55 of a code detecting relay is caused by occupancy of a track section, and at the same time it insures that variations in operating conditions will not cause a directional stick relay to be improperly 60 picked up when release of a code detecting relay occurs because the supply of coded energy over the rails of a track section is cut off for the purpose of deenergizing the track circuit apparatus.

My invention is advantageous in that no control pulse need be transmitted from the locations at each end of the single track block to an intermediate signal location, or from one intermediate signal location to another, to cause the 70 system to assume its deenergized condition. If the supply of coded energy from battery 2RTB, for example, is interrupted during a time when the system is set up for traffic to move from right to left, if no train is occupying the section 75 2R—6LT, the equipment at the intermediate sig-

nal location 6L—6R will assume its deenergized condition, as previously explained, and will cut off the supply of coded energy to section 6R—4LT, to thereby cause the release of the relays 4LH and 4LD at the other end of the single track block.

An additional advantage which is gained from this arrangement is that it causes all of the opposing signals governing traffic in the single track block to assume the stop position in case a train overruns the entering head block signal at the exit end of the block. If a train moving from left to right should pass signal 2RA at a time when signals 6L and 4LA are cleared for a train movement from right to left, the entrance of the overrunning train into detector section 1T will cause relay 1TR to release with the result that its front contact *a* interrupts the circuit for relay 2RCT. Accordingly, the supply of coded energy to section 2R—6LT is cut off, and as previously explained, the equipment at signal 6L and also at signal 4LA is restored to its deenergized condition with the result that the signals indicate stop.

The equipment operates in a manner similar to that described in the foregoing when the single track block is conditioned for traffic movements from left to right, when a train moves through the stretch from left to right, and when the system is being deenergized, and a detailed description of the operation of the equipment is deemed unnecessary.

It is to be understood that although only one set of intermediate signals, 6L and 6R, are shown in the drawings, the invention is not limited to this arrangement and any number of intermediate signals may be provided as necessary. Additionally, the conventional cut sections and hand-operated track switches equipped with electric locks may be interposed as desired without affecting the operation of the arrangement of equipment embodying my invention.

Although I have herein shown and described only one form of coded track circuit signaling system embodying my invention, it is to be understood that various changes and modifications may be made therein within the scope of the appended claims without departing from the spirit and scope of my invention.

Having thus described my invention, what I claim is:

1. In a coded track circuit signaling system, in combination, a stretch of railway comprising adjoining first and second track sections, means for at times supplying coded energy to the rails of said first section at the end thereof remote from said second section, a code following track relay connected across the rails of said first track section at the end thereof nearest said second section, a slow release relay energized as a result of operation of said track relay, means operative upon release of said slow release relay for momentarily connecting a battery and the winding of an auxiliary relay in series across the rails of said first track section at the end thereof nearest said second track section, said auxiliary relay having a normally released contact which becomes picked up or remains released according as the energy supplied through the winding of said auxiliary relay is of the value which is supplied when the portion of said first track section nearest said second track section is occupied or is of the value which is supplied when the portion of said first track section nearest said second track section is vacant, a directional

relay having contacts movable between a normal and an operated position, means responsive to picking up of the contact of said auxiliary relay for moving the contacts of said directional relay to their operated position, means responsive to picking up of the contacts of said slow release relay for moving the contacts of said directional relay to their normal position, and means effective when the contacts of said directional relay are in their operated position or the contacts of said slow release relay are picked up for supplying coded energy to the rails of said second track section.

2. In a coded track circuit signaling system, 15 in combination, a stretch of railway comprising adjoining first and second track sections, means for at times supplying coded energy to the rails of said first section at the end thereof remote from said second section, a code following track relay connected across the rails of said first track section at the end thereof nearest said second section, a slow release relay energized as a result of operation of said track relay, means operative upon release of said slow release relay for momentarily connecting a battery and the winding of an auxiliary relay in series across the rails of said first track section at the end thereof nearest said second track section, said auxiliary relay having a normally released contact which becomes picked up or remains released according as the energy supplied through the winding of said auxiliary relay is of the value which is supplied when the portion of said first track section nearest said second track section is occupied or is of the value which is supplied when the portion of said first track section is vacant, a directional stick relay having normally released contacts, a pick-up circuit for said directional stick relay established when the contact of said auxiliary relay picks up, a stick circuit for said directional stick relay including a front contact of said directional stick relay and interrupted when said slow release relay picks up, and means effective when the contacts of said directional relay are picked up or the contacts of said slow release relay are picked up for supplying coded energy to the rails of said second track section.

3. In a coded track circuit signaling system for a stretch of single track railway comprising adjoining first and second track sections, said first track section having at the end thereof nearest said second track section a transmitting relay having contacts which normally occupy a first position and are movable therefrom to a second position, said transmitting relay contacts being operative when in their first position to effectively connect the winding of a code following track relay across the rails of said first track section and being operative when in their second position to connect a track battery and the winding of a code following approach relay in series across the rails of said first track section, said signaling system including a signal governing entrance of traffic into said second track section from said first track section and having means governed by traffic conditions in said second track section for governing said signal and for at times operating the contacts of said transmitting relay between their two positions, said signaling system also including means for at times supplying coded energy to the rails of said first track section at the end thereof remote from said second track section, a first and a second slow release relay which are picked up in response to operation of said track relay, said second slow release relay

remaining picked up for a time interval subsequent to release of said first slow release relay on cessation of operation of said track relay, means effective when the contacts of said first slow release relay are picked up for supplying coded energy to the rails of said second track section at the end thereof nearest said first track section, an approach repeater relay effective when energized to establish a circuit for a lamp of said signal, and a directional stick relay effective when picked up to cause coded energy to be supplied to the rails of said second track section at the end thereof nearest said first track section while said first slow release relay is released, the combination with the foregoing apparatus of improved means for governing said approach repeater and directional stick relays by said code following approach relay, said means comprising means effective according as said second slow release relay is released or is picked up to condition said code following approach relay to pick up in response to energy of the value which is supplied through the relay winding when a train is present in said first track section within a substantial distance of the end of said track section nearest said second track section or to pick up only in response to energy of the value which is supplied through the relay winding when a train is present in said first track section within a relatively short distance of the end of said track section nearest said second track section, a circuit including a front contact of said code following approach relay for supplying energy to said approach repeater relay, and means responsive to picking up of the contact of said code following approach relay while said second slow release relay is picked up for supplying energy to said directional stick relay.

4. In a coded track circuit signaling system for a stretch of single track divided into track sections, said signaling system comprising code transmitting means and a code following track relay associated with each end of each of said track sections, decoding means responsive to the coding operation of each track relay except those for the extreme ends of the stretch for governing the operation of the code transmitting means for the adjacent end of the adjoining track section, manually controlled means for each end of said stretch for rendering the associated code transmitting means active and thereby cause transmission of code pulses over the track rails of the successive track sections toward the opposite end of the stretch for preparing the stretch for one direction of train movement, and a directional stick relay associated with each of said track relays except those for the extreme ends of the stretch and effective when energized to cause operation of the code transmitting means for the adjacent end of the adjoining track section, the combination with the foregoing apparatus of improved means for picking up said directional stick relays when and only when release of the associated decoding means is caused by entrance into the corresponding section of a train moving in the established traffic direction, said means comprising means effective upon release of the code detecting means at an end of a section to momentarily connect in series across the rails of the associated section at that end of the section a source of current and the winding of an auxiliary relay having a contact which remains released or becomes picked up according as the energy supplied from said source through said auxiliary relay winding is of the value which is

supplied when the portion of said track section at that end of the section is vacant or is of the value which is supplied when the portion of said track section at that end of the section is occupied, and means responsive to picking up of one of said auxiliary relays for supplying energy to the associated directional stick relay.

5. In a coded track circuit signaling system for single track railroads, a stretch of single track divided into a plurality of track sections with a head block signal at each end for governing traffic in opposite directions into said stretch and with intermediate signals located at intervals in the stretch, code transmitting means and a code following track relay associated with each end of each of said track sections, decoding means responsive to the coding operation of each track relay for governing the indication of the associated signal, each of said decoding means except those at the extreme ends of the stretch being effective when energized to cause operation of the code transmitting means for the adjacent end of the adjoining track section, manually controlled means for each end of the stretch for rendering the associated code transmitting means active and thereby cause transmission of code pulses over the track rails of the successive track sections toward the opposite end of the stretch for preparing the stretch for one direction of train movement, each of said intermediate signals having associated therewith a code following approach relay responsive to the code pulses which are supplied to the adjacent end of the adjoining track section, each of said approach relays having a normally released contact which becomes picked up when the code pulses supplied to the associated track section are of the value which are supplied when a train advances in said section within a relatively long distance of said approach relay, each of said approach relays being effective when its contact is operated to energize a slow release repeater relay which when energized establishes a circuit for a lamp of the signal with which the approach relay is associated, each of said intermediate signals also having associated therewith a normally released directional stick relay effective when energized to cause operation of the code transmitting means for the adjacent end of the adjoining track section, the combination with the foregoing apparatus of improved means for controlling the pick-up circuits for said directional stick relays, each of said means comprising means effective on release of the decoding means governing an intermediate signal to momentarily connect across the rails of the section with which the decoding means is associated the code following approach relay associated with that end of said section and during this period rendering said code following approach relay responsive only to energy of the value which is supplied through the relay winding when the portion of said section within a relatively short distance of said code following approach relay is occupied by a train.
